UNITED STATES PATENT OFFICE.

ALOIS HELFENSTEIN, OF VIENNA, AUSTRIA-HUNGARY.

METHOD OF CARRYING OUT GAS REACTIONS IN AN ELECTRIC FURNACE.

1,169,817.

Specification of Letters Patent.

Patented Feb. 1, 1916.

Application filed November 18, 1911. Serial No. 660,999.

To all whom it may concern:

Be it known that I, ALOIS HELFENSTEIN, a subject of the Austro-Hungarian Emperor, and a resident of 50 Bastiengasse, Vienna, 5 XVIII, Austria-Hungary, have invented certain new and useful Improvements in Methods of Carrying Out Gas Reactions in an Electric Furnace, of which the following is a specification.

10 It is known to carry out gas-reactions at a high temperature in the electric high tension flame, as it is the case with the known air combustion methods. The high tension flame has only a limited applicability, as it 15 allows of producing reactions between gases only, it however does not allow of disposing of solid or liquid bodies in a simple manner, so that these bodies can participate in the reaction of the gases, be it as catalysts or as 20 chemically active substances. The high tension flame is further limited with regard to the load it may carry, so that it has hitherto not been considered advisable to load the devices with more than 1000 kilowatts. The 25 high tension flame furthermore requires special provisions for igniting and maintaining the flame, and also complicated devices for controlling the current, and lastly special measures for the safety of the operators.

30 The low tension furnace, on the contrary, is far better adapted for carrying out gas-reactions, as it shows none of these difficulties and may besides work with far greater energies per furnace. The low tension furnace 35 has been proposed as resistance furnace for carrying out gas-reactions so for instance in the German Patent 148,457. Here a granular resistance charge is arranged between the fixed electrodes, and is heated to a 40 high temperature on the current passing through it. The gases to be submitted to the reaction are sent through this granular resistance charge.

The object of the present invention is like- 45 wise to carry out gas-reactions in an electric low tension resistance furnace, but here contrary to the German Patent 148,457 a fused or also granular material is arranged as resistance charge between vertical (hanging) 50 electrodes and the sole of the furnace which is preferably a conductor. The fused bath provided above the sole of the furnace will, namely admit of an accurate regulation of the vertical electrodes when also solid, 55 granular materials are provided for contact-

ing or relation purposes between the bath and the vertical electrodes. Into this fused bath or into the granular material above the same the gases to be brought to reaction are blown and will be heated by the electrically 60 heated resistance bodies to such a temperature that the reaction will take place between the several gases or between the gases and the solid or molten components of the resistance charge respectively. 65

For the gases to be introduced in the most simple manner into the highly heated reaction zone, they may be sent into the furnace through a bore in the vertical electrodes; or they may also be introduced 70 through the sole of the furnace.

The fused or granular resistance charge may be brought directly to reaction by their being electrically heated, and yield secondary products, besides the gas-reactions proceeding on them; these secondary products may then be drawn off periodically. 75

When the fused or granular charges actively participate in the gas-reaction or when they yield secondary products the 80 thereby consumed quantities are preferably replenished continuously around the electrodes.

In Figures 1 and 2 of the accompanying drawing a constructional form of the furnace adapted for carrying out the present method is exemplified in a vertical longitudinal and a horizontal section respectively. 85

The gas or the mixture of gases is introduced through pipe 1 into the vertically 90 suspended feeder 2 for the electric current and thence conducted into the electrode 3, entering at the lower end of the latter into the molten bath 7 which has accumulated above the conductive sole 6. Above this bath 95 is arranged the granular contacting or reaction charge 4, which may be replenished through the tubes 5 accordingly as it is consumed by the process. This charge surrounds the vertical electrode on all sides and 100 will therefore be always present in a sufficient quantity in the reaction chamber, so much the more as the movement of the vertical electrode, while it is being regulated, will greatly assist in inducing the charge to 105 settle down.

The gas or the gas mixture which has been introduced into the furnace will then be brought to reaction at the highly heated resistance charge and the gaseous or vaporous 110

products will escape at the sides through the banks of the charge into the chamber 8 disposed at a lower level whence they pass, preferably after condensing agents have 5 been introduced (through nozzles 9), through flues 10 into the collecting chamber 11.

As an example of a reaction to be carried out according to this method I shall now describe 10 the combination of acetylene and nitrogen to prussic acid or cyanid of hydrogen.

Acetylene and nitrogen are introduced in equal volumetric quantities according to 15 formula

20 through the vertical electrode into a slag bath heated to a high temperature by the passage of an electric current; the slag forming said bath consisting for instance of argillaceous earth on this slag bath floats 25 animal coal or charcoal as a contacting material, in which the components are united in an undisturbed process. The product is on leaving the electric heat zone received by an alkaline condensing agent, as for instance 30 milk of lime and proceeds to its further purification and recovery.

As another example of a reaction in which a granular material over the molten bath actively participates in the production of 35 tetrachlorid of carbon the introduction of charcoal, sulfur and chlorin into an electrically heated mixture of charcoal and sulfur vapor arranged above a bath consisting preferably of a molten inert silicate slag 40 may be cited, whereby the chlorin, which is intermediately bound to sulfur, will combine with carbon to tetrachlorid of carbon, while the sulfur is either absorbed in the slag bath or may be recovered in a vaporous 45 state.

As an example of a gas-reaction, in which also the electric heating bath participates the combining of silicon with nitrogen to 50 siliconated nitrogen may be described. The bath here consists of molten quartz into which nitrogen is blown. Over the bath (quartz bath) is arranged a layer of carbon, which will effect the reduction of the quartz to silicon; the silicon thus produced will 55 combine with the highly heated nitrogen to siliconated nitrogen, which may be recov-

ered as such or be further treated in the furnace.

This method may also be modified by electrically heating quartz or carbon as resistance charges over the molten bath (quartz bath) which facilitates the regulation of the electrodes; at the high temperature prevailing 60 silicon is produced; into these granular resistance charges (reaction charges) nitrogen is then blown, which will combine with the silicon and form siliconated nitrogen. 65

I claim:

1. The process of producing gas reactions 70 at high temperatures in electric low tension furnaces consisting in blowing the gases to be brought to reaction into a molten bath, the molten bath being adapted to participate in the reaction as a contacting agent and as a component of the reaction, and leading the highly heated gases and gaseous products of the reaction through solid granular materials above said bath, substantially 75 as described.

2. The process of producing gas reactions 80 at high temperatures in electric low tension furnaces consisting in blowing the gases to be brought to reaction into a molten slag 85 bath, floating coal on said bath as contacting material, uniting the components in an undisturbed process, and finally recovering the products, substantially as described.

3. The process of producing gas reactions 90 at high temperatures in electric low tension furnaces, consisting in blowing the gases to be brought to reaction into a molten quartz bath, and in finally recovering the products, substantially as described. 95

4. The process of producing gas reactions 100 at high temperatures in electric low tension furnaces, consisting in blowing nitrogen into a molten quartz bath blowing the gases to be brought to reaction into a bed of solid granular materials above the molten bath serving as contacting agents and components of reaction, and effecting reactions of said granular material and finally recovering the products. 105

In testimony whereof I affix my signature in presence of two witnesses.

ALOIS HELFENSTEIN.
